UNITED STATES PATENT OFFICE.

CLARENCE E. OGDEN, OF CINCINNATI, OHIO, ASSIGNOR TO THE KODEL RADIO CORPORATION, A CORPORATION OF OHIO.

RECTIFYING UNIT AND METHOD OF PRODUCING THE SAME.

Application filed June 27, 1927. Serial No. 201,683.

My invention relates to rectifying units, particularly of the copper oxide type.

In the construction of rectifiers made up of units of the copper oxide type, in order to 5 provide a rectifier of comparatively high capacity it is necessary that the rectifying units be of considerable area, and by reason of this I have found that during the necessary heat treatment for the production of the units, the 10 plates are extremely apt to warp and lose their flat shape so that it becomes difficult properly to assemble the units for the construction of the rectifier, and the resultant assembly lacks neat and symmetrical appearance which is 15 maintained when the units are not thus deformed.

The present invention therefore has for its principal object the construction of rectifying units in which the liability to such warping and deforming is overcome.

In the drawings:

Figure 1 indicates a rectifying unit constructed in accordance with this invention.

Figure 2 is a section of a unit constructed 25 in accordance with this invention.

Figure 3 is an elevation of an assembly of such units in a rectifier.

The numeral 1 indicates a plate preferably of metallic copper. The plate 1 by means of 30 heat treatment and cooling is provided with layers of oxide 2. For the formation of this oxide the plate 1 must be placed in an electric

or other furnace and the temperature raised to approximately 1900 degrees Fahrenheit, during which process the plate being of considerable area is apt, and in fact almost invariably does, warp and become misshapen. This warping is obviated by means of ribs 3 which are formed in the metal by means of suitable dies at the time that the plates are 40 stamped. The ribs 3 are so irregularly disposed in the plate that a rib or ribs are presented at an angle to the line of any possible warping bend in the plate itself during heat treatment, and such ribs therefore stiffen the plate and prevent the deformation. The plate is provided with a perforation 4 by means of which it is assembled or stacked with others upon a bolt 5 in the usual manner.

Having thus fully described my invention, 50 what I claim as new and desire to secure by Letters Patent is:

1. The method of producing a rectifying unit, comprising the forming of a metal plate with ribs irregularly disposed in its surface, 55 then heat treating said plate to form an oxide thereon.

2. As an article of manufacture, a rectifying unit, comprising a plate having a layer of oxide, and a plurality of ribs formed in and 60 irregularly disposed on said plate so as to reinforce the same against warping.

CLARENCE E. OGDEN.
